(57) **CLAIM**

I claim the ornamental design for a folding tweezers, as shown and described.

DESCRIPTION

FIG. 1 is a perspective view of a tweezers showing my design in the closed position;

FIG. 2 is a perspective view of the tweezers in the open position;

FIG. 3 is a top view of the tweezers in the closed position;

FIG. 4 is a sectional view of the tweezers' head section with the tweezers in the closed position take along lines 4—4 in FIG. 3.

FIG. 5 is a top view of the tweezers in the open position; and,

FIG. 6 is a right side view of the tweezers in the open position.
